Specification for Design.

Patented Dec. 28, 1920.

Application filed January 22, 1920. Serial No. 353,334. Term of patent 14 years.

To all whom it may concern:

Be it known that I, HENRY L. FERRIS, a citizen of the United States, residing at Harvard, county of McHenry, and State of Illinois, have invented a new, original, and ornamental Design for a Display-Stand for Drinking-Fountains for Stock, of which the following is a specification, reference being had to the accompanying drawing, forming a part hereof, in which—

Figure 1 is a side elevation of the ex-

hibiting stand with the water-bowl in place, and Fig. 2 is a rear elevation of the same.

I claim:

The ornamental design for a display stand for drinking fountains for stock, as shown.

HENRY L. FERRIS.
